PATTERN

Eric H. Zahn, Pound Ridge, N. Y., assignor to
 Austenal Laboratories, Incorporated, New
 York, N. Y., a corporation of New York

Application July 22, 1944, Serial No. 546,160

5 Claims. (Cl. 22—163)

1
 This invention relates, in general, to the art of casting, and has particular relation to an improved pattern.

One of the main objects of the present invention is to provide an improved pattern for forming a casting cavity in a refractory mold, which pattern is collapsible for removal from the mold and adapted for repeated use.

Another object of the invention is to provide a collapsible pattern composed of a relatively tough material resistant to wear and to the constituents of the refractory mold material and to the abrasive character of such material and self-parting relative to the mold material; more particularly, a hollow collapsible pattern composed of rubber or rubber-like material.

Another object of the invention is to provide a pattern which is collapsible to an extent to permit removal from an undercut mold without the necessity of making the mold of multi-section construction to permit removal of the pattern; also without requiring taper or draft in the mold for removal of the pattern.

Another object of the invention is to provide means for maintaining during formation of the refractory mold the hollow collapsible pattern shaped to form a casting cavity corresponding to the article to be produced, and means for collapsing the pattern for removal from the mold.

Further objects and advantages of the invention will appear from the following detailed description, taken in connection with the accompanying drawings in which:

Figure 1 is a side elevational view of one simplified and illustrative form of master pattern showing same applied to an insert for forming the mold cavity in which the collapsible pattern is produced;

Figure 2 is an end view of the pattern and insert shown in Figure 1;

Figure 3 is a sectional view of the insert which is placed in the mold cavity formed by the master pattern and insert shown in Figures 1 and 2 for completing the configuration of the mold cavity and imparting the hollow form to the collapsible pattern;

Figure 4 is an end view of the insert shown in Figure 3;

Figure 5 is a sectional view showing the mold produced from the pattern and insert of Figures 1 and 2, with the insert of Figures 3 and 4 in place for imparting the hollow form to the collapsible pattern;

Figure 6 is a top plan view showing the hollow collapsible pattern applied to an insert for main- 55

2
 taining the pattern shaped to form a casting cavity corresponding to the article to be produced;

Figure 7 is a sectional view showing, in more or less simplified form, the step of forming the refractory mold from the hollow collapsible pattern;

Figure 8 shows the step of collapsing the pattern for removal from the refractory mold;

Figure 9 is a side elevational view of the hollow flexible pattern for forming the crucible;

Figure 10 is a top plan view of the pattern shown in Figure 9;

Figure 11 is a sectional view showing the step of forming the crucible; and

Figure 12 shows the crucible of Figure 11 applied to the refractory mold for introducing into the mold cavity the metal, alloy or other material having the desired properties for the finished casting.

Referring to the drawings, the master pattern 5 is shaped to the configuration of the article to be produced, and preferably follows all fine detail of such article. It may be formed of metal, alloy or other suitable material, and in fact may be an actual specimen of the cast metal article.

The shape of the pattern 5 will vary according to the article to be cast. The particular master pattern selected for illustration is in the form of a concave worm wheel, pinion, cog wheel or the like, having an axial opening 6 provided with a groove or key-way 7. The insert 8 has a flange or head at 9 and a shaft 10 which removably fits the opening 6 and is provided with a key or spline 11 fitting the groove or key-way 7. The pattern 5 and insert 8 preferably have a high degree of surface smoothness and are otherwise of a character to impart a high degree of smoothness to the molding surfaces of the mold sections formed about pattern 5 and insert 8.

In the practice of my invention I form a sectional mold about the pattern 5, for example, in the manner more fully disclosed in Patent No. 2,306,516, issued December 29, 1942, to Eric H. Zahn, and in the copending application of Eric H. Zahn, Serial No. 524,025, filed February 26, 1944, now Patent 2,459,402 issued January 18, 1949. The resulting sectional mold comprises, as shown in Figure 5, mold sections 12 and 13 composed of any suitable material—preferably a low fusing alloy, such as a tin-bismuth alloy—as more fully described in the Zahn patent above mentioned. The mold sections 12 and 13 are preferably reinforced by outer reinforcing flasks or mold parts 14 and 15 composed, for example, of

cast iron or other suitable material. Upon completion of the sectional mold 12, 13, the sections of this mold are separated and the master pattern 5 and insert 8 are removed, leaving a mold cavity shaped at 16 to the configuration of the article to be produced and following all fine detail of the master pattern.

The next step is to form the hollow collapsible sub-master pattern in the sectional mold 12, 13. In accomplishing this, the mold sections 12 and 13 are placed together, with the insert 18 disposed, as shown in Figure 5, in the cavity 16 formed by the master mold 5 and insert 8. The insert 18 (Figures 3 and 4), which is preferably formed of metal and has a high degree of surface smoothness, has its base (Figure 5) supported in the cavity portion 19 formed by the base of the insert 8. Insert 18 has an extending annular portion 19' for imparting the hollow form to the collapsible pattern, and an extending shaft part 20 provided with a key or spline 21 for forming in the collapsible pattern an opening corresponding to the opening 6 in the master pattern and a groove or key-way corresponding to the groove or key-way 7 in the master pattern.

The mold sections 12 and 13 are preferably provided with locating or positioning dowels or other suitable means (not shown) for assuring accurate positioning of the mold sections relative to each other. With the insert 18 in place in one mold section, the cavity 16 of this section and the cavity 16 of the other section may be filled, as far as possible, with a suitable rubber or rubber compound in an uncured condition. Upon placing the mold sections 12 and 13 together, they are held tightly and securely together, preferably under pressure. If desired, with the mold sections 12 and 13 held together, the mold cavity may be further filled by forcing rubber or rubber compound through opening 24 so as to expel, as far as possible, all air from the mold cavity.

Thereafter, and with the mold sections 12 and 13 held together, preferably under pressure, uncured rubber, rubber compound, latex or other suitable rubber or rubber-like material, natural or synthetic, is injected under pressure into the mold cavity 16 through the opening 24, and the rubber or rubber-like material is cured preferably while the pressure is maintained. The rubber or rubber-like material is of such character that it will cure at a temperature below that which will soften or otherwise deleteriously affect the mold sections 12 and 13.

By curing the rubber or rubber-like material while maintaining it under pressure I assure that the mold cavity is completely filled, and thereby produce a hollow collapsible sub-master pattern 26 shaped externally to the configuration and following all fine detail of the article to be produced. The mold sections 12 and 13 are then separated, whereupon the pattern 26 and insert 18 are removed and the pattern 26 may then be removed from the insert 18. The sprue element may be cut off flush with the end of the pattern 26, and the hollow collapsible pattern is then ready for use.

The resulting hollow collapsible pattern 26 of rubber or rubber-like material is adapted for repeated use, which avoids the necessity of making a new pattern for each new refractory mold as required where a pattern formed, for example, of wax is employed. The pattern 26 is tough, resistant to wear and to the constituents of the refractory investment material forming the bonded refractory mold or mold part, and is also

resistant to the abrasive character of the refractory mold material and self-parting relative to such material. The pattern is of a character to give a high degree of surface smoothness and detail to the casting surface of the refractory mold. The articles produced in the mold cavity formed by the pattern 26 are cast with a high degree of surface smoothness and detail, and require little, if any, finishing of the articles after the casting operation.

The pattern 26 is used to produce the refractory mold, for example, by applying it to an insert 28 which has a base 29 and an extending annular part 30 fitting the hollow interior of the pattern 26 to maintain the pattern shaped to form a casting cavity corresponding to the article to be cast. Air holes or vents may be provided at 31 for assuring that the hollow interior of the pattern 26 conforms snugly to the insert 28. A heat resisting frame or investment flask 32 is applied and located relative to the insert 28, for example, by positioning or locating dowels 33.

The frame 32 is then filled, through the opening 34, with a wet mix of refractory investment material which may be any known or other suitable investment material such, for example, as the plastic mix disclosed in the copending application of Paul F. Collins, Serial No. 450,619, filed July 1, 1942, now Patent 2,380,945 issued August 7, 1945. The wet or plastic mix is preferably packed tightly, for example, by vibration, against the surface of the pattern 26, and is then permitted to set to form the rigid and self-sustaining or bonded refractory mold 35.

The insert 28 is then removed and a plate 38 is applied, as shown in Figure 8, this plate being positioned relative to frame 32 by the locating dowels 33. The plate 38 has an opening 39 which opens into the hollow interior 40 (Figure 8) of the pattern 26. By applying, for example, a hose connection 41 to a vacuum pump (not shown) the hollow interior of the pattern 26 may be evacuated or the pressure therein reduced sufficiently to cause the pattern to collapse for removal from the mold 35, notwithstanding the undercut character of the mold due to the concave form of the periphery of the pattern. The pattern 26 may then be again applied to insert 28 and used for making further refractory molds. Due to its resilient character the surface of the pattern against which the refractory mold is formed will, after collapse or distortion, spring back to the configuration for accurately producing the desired article.

In the particular embodiment of the invention selected for illustration, a hollow collapsible pattern 46 (Figures 9 and 10) is formed generally in the manner and preferably of the material described in connection with the formation of the hollow collapsible pattern 26.

The hollow collapsible pattern 46 is applied to an insert 48 which has a base 49 and an extending part 50 fitting the hollow interior of the pattern 46 to maintain pattern 46 shaped to form the desired molten metal receiving or pouring opening 52 in the crucible 53. An air hole or vent may be provided at 54 for assuring that the pattern 46 conforms snugly to the insert 48. A heat resisting frame or investment flask 56 is applied and located relative to the insert 48, for example, by positioning or locating dowels 58. A plate 60 may be applied to the frame 56 as shown in Figure 11.

The frame 56 is then filled, through the opening 62, with a wet mix of refractory investment

material, which may be any known or other suitable investment material, such, for example, as the plastic mix referred to in connection with the formation of the refractory mold part 35. The refractory crucible part 63 may, for example, be introduced through the opening 64 in the plate 60. The wet or plastic mix is preferably packed tightly, for example, by vibration, in contact with the hollow collapsible pattern 46 and is then permitted to set to form the rigid and self-sustaining or bonded crucible 53 with its crucible part 63. The insert 48 and plate 60 are then removed, whereupon the pattern 46 may be collapsed and withdrawn and the crucible 53, with its crucible part 63 applied to the refractory mold 35, as shown in Figure 12.

While I have described the crucible 53 as poured separately from the mold 35, it is to be understood that the crucible may be poured against the mold, or the mold poured against the crucible, if desired; thus to assure accurate fit and conformity between the refractory mold 35 and the crucible 53.

Upon application of the crucible 53 to the refractory mold 35, metal, such as a cobalt-chromium alloy or other high fusing metal or alloy, or other material having the desired properties for the finished casting, is poured or otherwise introduced into the mold cavity 70 (Figure 12) through the opening 52 in the crucible. If desired, vacuum may be applied to the opening 34 in the frame 32 (Figure 12), and thus through the relatively porous body of the refractory mold 35 to draw the molten metal into the mold and thus assure complete filling of all detailed formations of the mold cavity 70. The resulting casting, which may have extreme hardness and be difficult to machine, has a high degree of surface smoothness and detail, and requires little, if any, finishing of the article after the casting operation. After the casting has been made, the refractory mold 35 may be broken to permit removal of the casting, as well understood in the art.

I do not intend to be limited to the precise details or to the precise embodiment of the invention shown and described, as variations in the details and other embodiments are contemplated within the scope of the appended claims.

I claim:

1. A pattern for forming in a relatively rigid and unitary mold body, a mold cavity having a molding surface along the sides and inner end of the cavity with an undercut formation in the surface of the cavity and an opening leading from the mold cavity to the exterior of the mold body, said pattern comprising a rigid insert, and an outer resilient member of hollow form and of a character completely to cover the sides and inner end of said insert and having an opening 60 leading from its hollow interior for insertion of

said rigid insert into and removal of said insert in unitary form from the hollow interior of the resilient member, said rigid insert and resilient member having cooperating surfaces free of undercut formation, and said resilient member having an outer surface provided with an undercut formation thereon backed by said rigid insert when in place in the resilient member, said resilient member being of resilient character throughout its thickness to permit collapse of said resilient member, upon removal of the rigid insert from the resilient member, sufficient to free the undercut formation on the resilient member from the undercut formation in the surface of the mold cavity for separate removal of said resilient member from the mold cavity.

2. A core according to claim 1 wherein the outer resilient member consists essentially throughout its thickness of rubber-like material, with the inner surface of the rubber-like material cooperating directly with the rigid insert and the outer surface of rubber-like material presented directly to the surface of the mold cavity.
3. A core according to claim 1 wherein the rigid insert consists essentially of metal.
4. A core according to claim 1 wherein there is a base carried by the rigid insert and of a character to close the adjacent open side of an investment flask in forming the mold body.
5. A core according to claim 1 wherein the rigid insert has at least one vent opening of a character to lead from the place of cooperation of the inner surface of the resilient member with the outer surface of the insert and through said rigid insert to the exterior thereof.
